CLAIM

The ornamental design of a gear as shown and described.

DESCRIPTION

FIG. 1 is a front, top, left side perspective view of the gear having 60 teeth, showing our new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front side elevational view thereof; and,

FIG. 7 is a rear side elevational view thereof.

1 Claim, 5 Drawing Sheets
